UNITED STATES PATENT OFFICE.

LUDOVIC ESTIS HUNT, OF SPRINGFIELD, MISSOURI.

ENGINE-INDICATOR.

1,376,883.

Specification of Letters Patent.

Patented May 3, 1921.

Application filed March 31, 1919. Serial No. 286,306.

To all whom it may concern:

Be it known that I, LUDOVIC E. HUNT, a citizen of the United States, and a resident of Springfield, in the county of Greene and State of Missouri, have invented certain new and useful Improvements in Engine-Indicators, of which the following is a specification.

My invention is an improvement in engine indicators, and has for its object to provide mechanism for use in engines of any character, for indicating and recording the steam pressure at any port, the direction of movement and the relation between the operation of the valves and the said movement.

In the drawings:

Figure 1 is a side view of a drive wheel of a locomotive, with the controlling mechanism in place;

Fig. 2 is a front view, with parts in section, of the device for indicating valve setting;

Fig. 3 is a vertical section through the switch mechanism;

Fig. 4 is a view similar to Fig. 3, showing the fluid pressure controlled operating mechanism for the switch;

Fig. 5 is a diagrammatic end view of the recording mechanism;

Fig. 6 is a top plan view;

Fig. 7 is a view of a card formed by the recorder;

Fig. 8 is a diagrammatic view of the wiring.

In the present embodiment of the invention means is provided for use in connection with the driving wheels for indicating the movement of the same, whether in the forward or reverse speeds, mechanism for use in valve setting and testing to indicate the time of admission and exhaust mechanism for connection with the various ports to indicate the pressure, and recording mechanism to record the results of the above mentioned mechanisms.

In Fig. 1 the drive wheel 1, which is of usual construction, is secured to the axle 2, which is journaled in the journal box 3, and is lubricated from the oil cellar 4. This cellar is held in place by a nut and bolt 5 in the usual construction, and on the ends of the bolt a pair of arms 6 is arranged, one arm being at each end of the bolt.

Each arm has an outward extension 7 at its upper end, and each of these extensions

carries a switch plate 8, the arms extending in opposite directions and being so arranged that the switch plates 8 are diametrically opposite each other on the wheel and in exact horizontal alinement with center of axle 60 2. The arms are clamped against the journal box by means of a turn buckle 9, the said turn buckle being arranged between the lower ends of the arms and acting to move the said arms outwardly at their lower ends. 65

Each switch plate 8 carries a pair of contact buttons 10, and with these buttons is adapted to coöperate a switch arm 11 pivoted on a switch plate and arranged to contact with the buttons in alternation when it 70 is swung in opposite directions. These switch arms are controlled by a pin 12 which is mounted on an arc shaped bar 13 secured to the spokes of the wheel. The pin 12 is in exact alinement with a line through the centers of the axles 2 and the main pin 14.

It will be obvious that when the wheel rotates in the forward direction the pin 12 will engage the switch arms 11 in alternation and will move the arm at the right 80 of Fig. 1 to contact with the button at the top, while it will move the arm at the left to contact with the button at the bottom. The arrangement is such that each switch arm closes the normally open circuit in 85 which the contact buttons are interposed.

When the wheel moves in the reverse the switch arms will be operated in the opposite directions to close another circuit which is connected with the lower contact 90 button at the right and with the upper contact button at the left.

In Fig. 2 is shown a device for valve setting and testing. In this construction a cylinder 15 is provided, having one end threaded, 95 as shown, to engage within a port. At the opposite end the cylinder has longitudinally extending arms 16 which support a nut or internally threaded nipple 17 at the axis of the cylinder. A piston 30^a is arranged 100 within the cylinder, and a stem 18 is connected with the piston. This stem extends through an externally threaded sleeve 19 which has threaded engagement with the nipple 17, and the outer end of the sleeve 105 is enlarged and polygonal for engagement by a wrench to turn the same.

A coil spring 20 encircles the rod between the inner end of the sleeve 19 and a collar 21 on the piston. This collar is beveled as 110

shown, and is adapted to engage a switch arm 22 to operate the said arm, the arm being pivoted to a switch plate 23 supported by one of the arms 16. This switch plate 5 carries contact buttons 24, and when the piston moves in one direction it will be obvious that the switch arm will be caused to contact with one button while, when it moves in the opposite direction, the switch 10 arm will be caused to contact with the other button. These buttons and the buttons on the switch plates 8 before mentioned are interposed in circuits to be presently described.

15 By means of the sleeve 19 the tension of the spring 20 may be nicely regulated and mechanism shown at the right of Fig. 2 is provided for indicating the tension. This mechanism comprises an arc shaped bar 25 20 carrying a scale, secured to that arm 16 remote from the switch plate, and an indicator 26 in the form of a lever pivoted intermediate its ends, having one end coöperating with the scale and the other engaging 25 an annular groove in the inner end of the sleeve 19.

In Fig. 4 is shown mechanism for indicating the steam pressure at any desired point. This mechanism comprises a cylinder 30 27 having one end threaded to engage within an opening, and having at the other end a pair of longitudinally extending arms 28 which, at the end remote from the cylinder, carry an internally threaded nipple or nut 29. A piston is arranged within the cylinder, and a rod 30 extends from the piston, the said rod having rack teeth as shown. The outer end of the rod extends through a sleeve 31 similar to the sleeve 19 of Fig. 40 2, and a coil spring 32 encircles the rod between the inner end of the nut and a stop collar 33 on the rod. By means of the nut the tension of the spring may be varied, and the tension of the spring is indicated by 45 the mechanism indicated at 34 at the right of Fig. 4 and is similar to that shown at the right of Fig. 2.

The teeth of the rack bar are engaged by a pinion 35 which is secured to a switch 50 shaft 36 journaled in the upper arm 28, and this shaft carries a switch arm 37 which has an extension moving over the ends of a series of contact bars 38. These bars are arranged in annular series, and the rotation 55 of the switch arm will contact with all of the bars during its complete rotation with the shaft 36. These contact bars 38 are supported by a shaft 39, which is a guide pin for insuring the proper engagement of the 60 bars, and the shaft also carries a series of bars 40, arranged in annular form and corresponding in number and arrangement to the bars 38.

Each bar 40 carries a contact pin 41 which 65 is adapted to engage and fit tightly within

an opening in the adjacent end of a bar 38. The shaft also supports one of the sections 42 of a casing, the other section 43 being supported by the shaft 36. These casing sections telescope at their adjoining ends, 70 to form a closed casing for the switch mechanism. The lead wires for the circuits to be described are connected with the bars 40, and it will be obvious that when these bars are pushed home against the bars 38, the 75 bars 38 will be connected with the lead wires.

A number of circuits are provided, the number corresponding to the number of places to be tested. In locomotive work each side is equipped alike, that is, the right and 80 left hand main wheels have the equipment shown in Fig. 1. The cylinders which are, in effect, independent engines, have the equipment shown in Fig. 27, the cylinders 4 being arranged at the points to be tested. 85

In the recording device shown in Figs. 5 and 6, a suitable casing 44 is provided, and longitudinally of this casing is journaled a platen roll 45, a feed roll 46 and a paper supporting roll 47, the roll 47 being outside 90 of the casing as shown. The strip 48 of paper passes from the roll 47, beneath the roll 46 and over the roll 45, and an ink ribbon, indicated at 49 moves longitudinally of the platen roll above the paper. A series of 95 levers 50 are pivoted intermediate their ends just behind the platen roll, and each lever has at its forward end a depending portion 51 acting as a pin or stylus to mark upon the paper when the lever is swung in the proper 100 direction.

A coil spring 52 normally draws each stylus away from the paper, and the opposite end of each lever has an armature 53 which coöperates with the cores of a magnet 54 105 supported in the casing. The arrangement is such that when any electro-magnet is energized the corresponding lever 50 will be operated to cause the stylus to press upon the paper on the platen, and because of the 110 ink ribbon an impress or permanent record will be made on the paper. The platen is driven by a belt 54^a, which connects pulleys on the end of the platen and on the shaft of a suitable motor 55, or the platen may be 115 driven by the device being tested.

In practice, the number of levers will vary. For instance, in a simple locomotive there may be enough levers to register all ports and centers, that is, six levers for each 120 side of the locomotive. In addition there will be one lever for each ten pounds pressure the engine is expected to carry. For instance, two hundred pounds pressure would require twenty levers additional for 125 each side. Thus there would be fifty-two levers.

It will be understood that the mechanism shown in Fig. 2 is designed for valve setting and testing, a mechanism often desirable 130

when the results of a more elaborate test of power development are not desired. Hence to avoid complications the construction shown in Fig. 2 is used. If for instance, it is desired to test the valve setting on a simple locomotive the equipment shown in Fig. 1 is placed on the main journal box of a wheel as represented, one on each side of the locomotive. A well insulated wire is run from each contact member 10, the said elements being well insulated from the other parts. The wires are run in any convenient manner, to the construction shown in Fig. 6 and there connected, the wires from the right of Fig. 1 being connected to the right of Fig. 8 and the wires from the left of Fig. 1 to the left of said figure.

In order to dispense with the return wire, the switch arms 11 are grounded, and a general ground is made of the group of magnets, so that the return is through the frame of the locomotive. One of the devices shown in Fig. 2 is now placed at each end of the cylinder. If a simple locomotive four units are required, one on each side of each cylinder. When in place, the contact buttons 24 at the right of Fig. 2 are connected with the third and fourth keys from the right of Fig. 8, while the contact buttons 24 at the left of Fig. 2 are connected with the end keys of Fig. 6. Thus twelve wires are needed and twelve keys or levers 50 are used. It will be obvious that whenever a switch arm 11 is moved by a pin 12, whether the wheel is moving forwardly or in the reverse, a circuit will be closed and the key or lever 50 which is controlled by the said circuit will be depressed to register on the strip of paper. When the plunger in the cylinder 15 is moved in one direction the switch arm 22 will be operated to contact with one of the buttons 24 and the key or lever of the circuit which is closed by the contact of the switch arm with the said button will be depressed to register upon the paper.

The construction shown in Fig. 4 is an amplified or multiple form of that shown in Fig. 2 and is arranged to give a series of connections, as indicated by the segments 38, the said segments constituting what is in effect a commutator. It will be understood that this commutator is insulated and that each bar or segment is insulated from all the others. The switch arm 37, in practice, may be grounded on the frame or have a return wire, as may be desired. As the plunger 30^a is moved outwardly under the steam pressure it will be obvious that the switch arm will be rotated, contacting in succession with the bars of the segment, and since these bars are connected with the levers 50 the levers will be operated to record upon the strip of paper.

In using the Fig. 4 construction, the engine being tested, or the recording instru-

ments in Fig. 8, must be accurately timed, and in locomotive work it is essential that the recording instrument of Fig. 8 will be timed for speed, that is, the exact speed must be known in order to correctly compute the 70 value of the card.

In Fig. 8 is shown diagrammatically the wiring for the electrical circuits which control the indicating mechanism. Referring to this figure, it will be noticed that one terminal of each electro-magnet 54 is grounded, as indicated at 63. Lead wires 64 connect the buttons 24 with terminals of certain electro-magnets and other lead wires 65 connect the terminals of other of the magnets with 80 the contact bars 38. With this arrangement, it will be obvious that when a switch arm 11 contacts with either button 10 the current will flow from ground through the switch arm, the contact button, the lead wire 62, 85 and the magnet to ground, energizing the magnet and causing the lever pertaining thereto to function. Whenever the switch arm 37 contacts with a contact bar 38, the electromagnet connected therewith will be energized. It will be understood that each of the contact bars 38 is connected with an electro-magnet, as are also each contact button 10 and each contact button 24, it being understood, however, that the Fig. 2 construction 95 to which the contact buttons 24 pertain is used only in valve setting and is not used when the remaining construction is in use. In Fig. 7 is shown a portion of a card formed by the indicator.

In explanation of the card shown in Fig. 7, it will be understood that the legends "Back end cylinder" and "Front end cylinder" are merely explanatory and are not produced in the card. Neither are the lines 105 indicated "Usual card."

It will be understood that the instrument shown in Fig. 6 will, in practice, have more than twenty-eight keys, but the number twenty-eight will be taken for explanation. 110 One of the devices shown in Fig. 4 is placed at the front end of the cylinder and one at the back. The switch arm 37 will normally stand at zero or at that segment 38 indicating zero. The first key from the right hand end of the magnets of those keys at the right of the center of Fig. 6, with the exception of the two endmost magnets, are connected with the segments 38 of that instrument of the character shown in Fig. 4, which is arranged at the front end of the cylinder, and the magnets of the keys at the left of the center of Fig. 6, with the exception of the two endmost keys, are connected with the segments 38 of that instrument which is arranged at the rear of the cylinder.

The vibrating or make and break contact system is to be used and if at this stage the electric current is applied the above designated keys, that is, the levers 50, next but 130

one to each end, will begin to vibrate. With the paper moving it is obvious that a row of dots will be produced along the margin of the paper, a row at each margin, regardless of whether or not the engine is in motion. This is the atmospheric line and is shown on the card by the straight line of dots at each margin of the card.

When pressure is admitted to the cylinder 10 at either end it will cause the switch arm 37 to be swung a distance equal to that pressure above the zero or atmospheric line, and as the switch arm passes over the segments 38, which are consecutively connected to the 15 keys 50 in Fig. 6, each key will vibrate a number of times, depending upon the period of time it remains in circuit. If the segment pertaining thereto is passed over quickly but one or two dots will be produced.

20 It will be obvious that at the outer end of that row of dots indicating the full pressure, there is a line or dot marked on the center. This line or dot is produced by the first key 50 at each end of Fig. 6, and these 25 keys are connected with the contacts 10 of Fig. 1. Hence these keys will be operated each time the element 12 cuts the horizontal plane through the center of the wheel. It will be evident that as the pressure rises in 30 either end of the cylinder keys farther toward the center of the card will be actuated, producing the irregular line which marks the rise of pressure in that end of the cylinder.

35 The length of the card is irregular, unless the paper is driven by the same power which makes the card. In that case the same length of card obtains, regardless of the speed of the engine, which would be desirable if the 40 engine were traveling at a known rate of speed. In locomotive work, however, and in many other types of engines, the speed is an unknown quantity. Therefore, it is desirable to have means for accurately determining 45 the speed at the moment of taking the card. This means is provided for by regulating speed of Fig. 6 to a known quantity or number of revolutions per minute and in this manner the number of cards per minute 50 produced by Fig. 6 gives the revolutions per minute of engine under test. Cards are then obtained of varying length, but with positive pressure readings. For instance, in the twenty-four inch stroke engine each card 55 will represent a twenty-four inch piston travel in a given time, regardless of whether the card is two inches or two feet long, and a given number of cards per minute gives the revolutions of the engine. This, together with the fact that the paper is traveling at so many feet per minute, gives ample basis for all calculations of speed, power produced and the like. It will be understood that each segment 38 is connected with 60 one of the keys or markers 50.

I claim:

1. A device of the character specified comprising a cylinder for connection with a port of the engine to be tested, a piston in the cylinder and moved by the pressure in one direction, a spring for returning the piston, a series of devices for making permanent records and electrically controlled, an electrical circuit for each device, and a switch for controlling the circuits controlled by the movement of the piston, said switch comprising an annular series of contact bars, each bar being connected to one terminal of a circuit, a switch arm connected to the other terminals of the circuit and pivoted at the center of the series, and a connection between the piston and the arm for rotating said arm about its center, means for varying the tension of the spring, and means for indicating the said tension. 85

2. A device of the character specified comprising a cylinder for connection with a port of the engine to be tested, a piston in the cylinder and moved by the pressure in one direction, a spring for returning the piston, a series of devices for making permanent records and electrically controlled, an electrical circuit for each device, a switch for controlling the circuits controlled by the movement of the piston, said switch comprising an annular series of contact bars, each bar being connected to one terminal of a circuit, a switch arm connected to the other terminals of the circuits and pivoted at the center of the series, and a connection between the piston and the arm for rotating said arm about its center. 90

3. A device of the character specified comprising a cylinder for connection with a port of the engine to be tested, a piston in the cylinder and moved by the pressure in one direction, a spring for returning the piston, a series of devices for making permanent records and electrically controlled, an electrical circuit for each device, and a switch for controlling the circuits controlled by the movement of the piston. 95

4. A device of the character specified comprising a series of electrically controlled recording devices, a normally open electrical circuit for each device, a switch for controlling each of the said circuits, means for supporting a pair of switches adjacent to each main driving wheel at diametrically opposite points, means controlled by the rotation of the wheel for controlling the switches, said means comprising a pair of arms supported by the oil cellar and extending in diametrically opposite directions, each carrying a switch plate having contact buttons interposed in the circuits, a switch arm on each plate, and a pin on the wheel for engaging the arms. 105

5. A device of the character specified comprising a series of electrically controlled 110

- recording devices, a normally open electrical circuit for each device, a switch for controlling each of the said circuits, means for supporting a pair of switches adjacent to each 5 main driving wheel at diametrically opposite points, and means controlled by the rotation of the wheel for controlling the switches.
6. In a device of the character specified, 10 electrically controlled recording devices, a switch for controlling the said devices, and means controlled by the pressure in the engine cylinders for operating the switch to actuate the recording devices in sequence, 15 the pressure controlled device comprising a cylinder for connection with a port of the engine, a piston in the cylinder, and a connection between the piston and the switch for operating the same.
- 20 7. In a device of the character specified, a pressure controlled device for use in valve setting, comprising a cylinder for connection with the port of the engine, a piston in the cylinder, a switch supported by the 25 cylinder and comprising a pair of contact buttons, a switch arm for connecting with the buttons in alternation, and means on the piston for operating the arm at a predetermined moment in the movement of the piston, electrically controlled recording devices, 30 normally open electric circuits for the said devices, one terminal of each circuit being connected to a button of the switch and the other terminals to the switch arm.
- 35 8. A pressure indicating device for engines, comprising a series of electrically controlled recording devices, a normally open circuit for each device, switches for controlling certain of said devices and adapted to be 40 arranged adjacent to a rotating part of the engine and to be controlled by the rotation of the said part, a common switch for controlling the circuits of the other devices, and pressure controlled devices for connection 45 with the cylinders of the engines and connected to the common switch for controlling the same in accordance with the pressure in the cylinders, said pressure controlled devices each comprising a cylinder for connection 50 with a port of the engine, a piston in the cylinder, and a connection between the piston and the common switch for operating the same, and a spring normally forcing the piston toward the engine cylinder and regulated for the purpose specified.
- 55 9. A pressure indicating device for engines comprising a series of electrically con-
- trolled recording devices, a normally open circuit for each device, switches for controlling certain of said devices and adapted to be 60 arranged adjacent to a rotating part of the engine and to be controlled by the rotation of the said part, a common switch for controlling the circuits of the other devices, and pressure controlled devices for connection 65 with the cylinders and connected to the common switch for controlling the same in accordance with the pressure in the cylinders, said pressure controlled devices each comprising a cylinder for connection with a port of the engine, a piston in the cylinder, and a connection between the piston and the common switch for operating the same.
- 70 10. A pressure indicating device for engines, comprising a series of electrically controlled recording devices, a normally open circuit for each device, switches for controlling certain of said devices and adapted to be 75 arranged adjacent to a rotating part of the engine and to be controlled by the rotation of the said part, a common switch for controlling the circuits of the other devices, and pressure controlled devices for connection 80 with the cylinders of the engines and connected to the common switch for controlling the same in accordance with the pressure in the cylinders.
- 85 11. A pressure indicator for engines comprising a series of recording devices, a common strip of paper upon which all of the 90 devices record, said devices being arranged in alinement transversely of the paper, an open circuit for each of the said devices, switches for controlling the outermost devices adapted to be arranged at the opposite 95 sides of a rotating part of the engine and to be controlled by the rotation of the said part, a common switch for controlling the circuits of the other devices, and pressure controlled devices for connection with the 100 cylinder and connected to the common switch to operate the same in accordance with the pressure.
- 105 12. A pressure indicating device for engines, comprising pressure controlled devices for connection with the cylinders of the engine, a series of electrically controlled recording devices, a normally opened circuit for each device, and means controlled by the pressure controlled devices for closing the 110 circuits of the recording devices in sequence in accordance with the pressure in the cylinders.

LUDOVIC ESTIS HUNT.
